CLAMPING HOLDER FOR STOCKING FORMS

Filed April 4, 1930

FIG. 1.

FIG. 2.

FIG. 3.

UNITED STATES PATENT OFFICE

HUGO HEMMERICH, OF WYOMISSING, PENNSYLVANIA, ASSIGNOR TO BERKSHIRE KNITTING MILLS, OF WYOMISSING, PENNSYLVANIA, A CORPORATION OF PENNSYLVANIA

CLAMPING HOLDER FOR STOCKING FORMS

Application filed April 4, 1930. Serial No. 441,499.

This invention relates to form holding devices, and more particularly to the type used in the manufacture of hosiery for conveniently holding the wooden stocking drying forms in order to facilitate the application of the stockings thereon; an object of the invention being to provide an improved form holding device which is simple in construction, efficient in use and adapted to overcome the detrimental features of the devices heretofore produced for this purpose.

The invention comprises the novel elements, features of construction and arrangement of parts in cooperative relationship as hereinafter fully disclosed by the detailed description and accompanying drawing of one embodiment thereof, from which the above and other objects as well as attendant advantages will also become more readily apparent.

In the accompanying drawing:—

Fig. 1 is a perspective view of my improved form-holder or device, as it appears when secured to a drier or similar support.

Fig. 2 is a cross-sectional view, taken substantially as indicated by the arrows 2—2 on Fig. 1, and

Fig. 3 is a plan view of the device only partly broken away and as seen by looking in the direction of the arrows 3—3 on Fig. 2.

The form holding devices at present obtainable for the purpose mentioned, are constructed for direct mounting to the top or edge of a table plate. The stockings to be dried are usually piled on this plate near the device, in readiness for "boarding". When manipulating the stockings in applying them to the forms it frequently happens that they catch and are injured on the exposed parts of such a device.

In order to overcome this objectionable feature, my invention provides for attachment in such manner that the table plate is clear of obstructions or parts of the device, and it consists essentially of an adjustable bracket which carries form supporting and gripping means.

By referring to the drawing it will be noted that the bracket comprises two angle plates 9 and 9a, adjustably secured to each

other by the slot-and-screw-bolt arrangements 11.

The form supporting and gripping means comprises a stationary gripping member consisting of an inverted L-shaped plate 12 fixed to angle plate 9a by bolts 13, and a movable member or plate 14 which is rounded at 15, and bent at 16 to provide a seat for the bottom end of a form-board indicated at 17. The plate 14 is connected by hinges 18 to the lower end of a plate 19, which in turn is connected by hinges 20 to the bracket angle 9a. A resilient pad 22, of leather or the like, is secured to the inner surface of plate 14 by screws 23 and adapted to yieldingly engage the board 17 when the plate 14 is swung toward the plate 12 by the body of the operator indicated by the dot-and-dash line 0.

The device may be adjustably mounted to a suitable support, e. g. a drier 24 partially indicated and having a table plate 25 secured to its top by angles 26, by means of screw bolts 27 which pass through the angles 26 and slots 28 in the bracket-angle 9.

It will be noted that the adjustable arrangement of the bracket and the manner in which it is secured to a support affords proper and convenient positioning of the device clear of the table plate 25.

The plate 14 is normally separated from the plate 12 and maintained in the position shown in full in Fig. 2, by the action of gravity.

In operation, a form-board 17 is inserted between the gripping members or plates 12 and 14 and its bottom end placed on the seat 16. The operator then takes one of the wet stockings, which are piled on the table plate 25 near the device, and applies it to the upper free end of the form-board, at the same time pressing with his body against the rounded part 15 of plate 14 in order to grip the board, as shown by dot-and-dash lines in Fig. 2. During the manipulation of the stocking in fitting it onto the form-board the latter is withdrawn from the device and reversed, as well as tilted, the latter action being made possible by the hinged connection between the plate 19 and the bracket-angle 9a.

Of course, the device shown and described

may be changed and modified in various ways and it is therefore to be understood that the invention is not limited to the precise construction shown and described, but that it is capable of such changes and alterations as fairly come within the scope of the appended claims, considered in connection with the prior art.

I claim:

- 10 1. In combination with a work-holding table, a stocking form-clamping holder comprising a bracket rigidly secured with respect to said table, a fixed form rest secured to said bracket, a form-contacting member hingedly secured to said bracket and adapted to be swung toward and from said fixed rest, said bracket having means for adjusting the height of said form rest relative to the top of the work holding table.
- 15 2. In combination with a work-holding table, a stocking form-clamping holder comprising a bracket rigidly secured with respect to said table, a fixed stocking form rest secured to said bracket, a form-contacting member hingedly secured to said bracket and adapted to be swung toward and from said fixed rest, said bracket having means for adjusting the height of said form rest relative to the top of the work holding table and for
- 20 30 adjusting the spacing between the form rest and an edge of the table.
3. In combination with a work-holding table, a stocking form-clamping holder comprising a bracket rigidly secured with respect to said table, a fixed stocking form rest secured to said bracket, a form-contacting member having one end hingedly secured to said bracket and adapted to be swung toward and from said fixed rest, said bracket comprising a plurality of members slidable relative to each other for adjusting the height of said form rest relative to the top of the work holding table.
4. In combination with a work-holding table, a stocking form-clamping holder comprising a bracket rigidly secured with respect to said table, a fixed stocking form rest secured to said bracket, a form-contacting member having one end hingedly secured to said bracket and adapted to be swung toward and from said fixed rest, said bracket comprising a plurality of members secured together by slot-and-screw connection means for adjusting the height of said form rest relative to the top of the work holding table.
5. In combination with a work-holding table, a stocking form clamping holder comprising a bracket substantially positioned beneath said table and rigidly secured with respect thereto, a fixed form rest secured to said bracket, a member hingedly secured to and depending from said bracket, and a form-contacting member adapted to be swung toward and away from said fixed rest and comprising a form-seating platform, said form-

contacting member having one end hingedly secured to said depending member.

6. In combination with a work-holding table, a stocking form-clamping holder including a bracket rigidly secured with respect to said table, a fixed stocking form rest comprising an inverted L-shaped metal plate rigidly secured to said bracket and having its upper surface positioned substantially flush with the table top, a form-contacting member comprising a metal plate having one end hingedly secured to said bracket and adapted to be swung toward and from said fixed rest, said last named plate having a portion thereof bent at an angle to provide a laterally-extending form-seating platform adjacent its hinged end.

7. In combination with a work-holding table, a form-clamping holder comprising a table-carried bracket having a form rest fixedly positioned in spaced relation to the table edge, a form-contacting member swingable toward and from said fixed rest and having an angular form-seating platform, and a supporting member for said form-contacting member hingedly secured to said table-carried bracket and movable by the weight of the form-contacting member to normally support said contacting member swung away from said fixed form rest, said bracket having means for adjusting the height of said rest relative to the top of the work-holding table.

8. In combination with a work-holding table, a form-clamping holder comprising a table-carried bracket having a form rest fixedly positioned in spaced relation to the table edge, a form-contacting member swingable toward and from said fixed rest and having an angular form-seating platform, and a bracket-carried supporting member for said form contacting member hingedly secured to said table-carried bracket and movable by the weight of the form-contacting member to normally support said contacting member swung away from said fixed form rest.

9. In combination with a work-holding table, a form-clamping holder comprising a table-carried bracket having a form rest fixedly positioned in spaced relation to the table edge, a form-contacting member swingable toward and from said fixed rest and having an angular form-seating platform, and a connecting member having one end hingedly secured to said fixed bracket beneath said fixed form rest and its depending opposite end hingedly secured to said form-contacting member adjacent said form-seating platform, said connecting member forming a swinging support actuated by the weight of said form contacting member to normally swing the latter away from said fixed form rest.

In testimony whereof I affix my signature.

HUGO HEMMERICH,
